UNITED STATES PATENT OFFICE

2,168,088

MILL

Robert S. Butler, Claremont, N. H., assignor to
 Sullivan Machinery Company, a corporation of
 Massachusetts

Application December 31, 1934, Serial No. 759,908

24 Claims.

(Cl. 83—46)

My invention relates to size reducing mills, and more particularly to mills which are especially adapted for the reduction of masses of rock or retort residues, coal and other materials from sizes of a few inches in diameter to sizes of an inch or less in diameter. Generally, my invention is intended to perform more simply, cheaply and efficiently the operations of present commercial mills crushing corresponding sizes of material.

An object of my invention is to provide an improved size-reducing mill. Another object of my invention is to provide an improved crushing mill performing a maximum amount of useful work in proportion to the power consumption thereof. A further object of my invention is to provide a crushing mill of very simple construction and having a minimum number of moving parts, all of which are rugged and durable and subject to a minimum likelihood of breakage.

Still another object of my invention is to provide an improved size-reducing mill of the impact type, having improved feeding means and providing for the delivery to the material to be reduced in size of a maximum number of blows per unit of time. Yet another object of my invention is to provide an improved crushing mill in which, when the same is running idle, that is, with interrupted feed, a minimum of power will be required. Still another object of the invention is to provide for the most efficient use of the kinetic energy of the relatively moving parts of the mill. Yet another object of the invention is to provide a mill having cooperating, relatively movable elements of which one is substantially freely movable with respect to the other and in which friction will be reduced to a minimum. Other objects and advantages of my invention will hereinafter more fully appear.

According to one aspect of my invention, I have provided an improved mill in which a pair of relatively movable impact elements are brought together in such manner that both are mounted for oscillatory movement upon a common axis and power is positively transmitted to one of the same to effect oscillatory movement thereof, while the other derives its movement solely from the first, receiving no movement, however, from the positively driven element except when material to be reduced in size is being supplied to the device. According to another aspect of the invention, I have provided an improved mill in which a pivotally mounted chamber member supports one or more pivotally mounted size-reduc-

ing elements which are freely movable relative to the chamber member in so far as oscillation is concerned, but which are, due to an offset pivot relation, positively moved as to their points of pivotal support upon chamber oscillation. Other aspects of the invention will be hereinafter apparent and pointed out in the claims.

In the several embodiments illustrated, it will be noted that there is provided a positively moved chamber alternately oppositely moyed at a rapid rate in a predetermined path and providing portions performing the dual functions of a hammer and an anvil, which chamber encloses one or more cooperating size-reducing or crushing elements, each of which is pivotally movable, and which also perform conjoint hammer and anvil functions. It will further be noted that in the several species illustrated the mounting of the enclosed size-reducing (as illustrated: crusher) element is so arranged as to cooperate in the distribution of the material to be processed and to effect delivery of the material now at one point and now at another, so as to provide for the most effectual processing of the material delivered into the size-reducing chamber. In all forms of the invention illustrated, it will be observed that there are simultaneous motions in like direction and periodic simultaneous motions in relatively opposite directions on the part of the positively moved and the so-to-speak free crusher elements. While it will be evident that it is unnecessary to provide an oscillatory motion of the casing or housing member of the mill in order to attain certain of the advantages inherent in the use of pivotally supported, relatively free size-reducing crusher elements, none the less by pivotally mounting the casing and providing feed adjacent the pivotal mounting, it will be evident that a continuous feed and discharge of material may be effected in such manner as to provide for highly efficient processing and promote delivery of the fully reduced material through the aid of centrifugal force.

Upon the size of the material to be processed and upon its nature will depend in great measure the form and dimensions of the mill. The size of the material to be processed will determine the necessary dimensions of the casing adjacent the point of feed, and in plural "free element" mills will determine the spacing of these elements. The hardness of the material will determine the weights of the parts in a measure, and also the rate of movement of the parts. The size of the material will also have its effect upon the dimension of the chamber element, and the rate of

movement desired will be a factor in determining the stroke of the chamber element, that is, its range of oscillation and also the number of oscillations per unit of time. The stroke or range of oscillation of the chamber element will be a further factor in the chamber dimension. Since this mill is designed in its various forms to make maximum use of the kinetic energy of the relatively moving parts, obviously the amount of energy necessary to crush the maximum-sized piece of material will regulate the weight of the parts and their rates of movement, and a balance of weight and speed will be reached, having in mind that speeds of from six hundred to one thousand complete cycles per minute have been found to be desirable, though not essential, in practice. The designer, having selected a stroke and the weight of his parts, will readily determine their sizes, and will proportion his chamber so as to provide a dimension along the path of movement thereof approximately equal to one and one-half times the stroke plus one and one-half times the maximum material size plus the dimension along said path of the pivoted internal crusher element, these proportions being of course for the single, pivoted internal crusher element. Where a plurality of pivotally mounted crusher elements are to be used, the form which the modification should take is an obvious matter. A wide variation is possible, and particularly is this so if powerful impact is less essential, and so chamber shortening possible.

In the accompanying drawings, in which two forms, with a modification of one of the same, 35 which my invention may assume in practice, have been shown for purposes of illustration,—

Fig. 1 is a central vertical section through one illustrative embodiment.

Fig. 2 is a plan view of the structure shown in 40 Fig. 1.

Fig. 3 is a sectional view taken on a plane corresponding to the section line 3—3 of Fig. 1 with parts omitted.

Fig. 4 is a view similar to Fig. 1, showing a 45 modified form of construction.

Fig. 5 is a fragmentary view similar to Fig. 2.

Fig. 6 is a horizontal section on a plane corresponding to the line 6—6 of Fig. 4, with parts omitted.

50 Fig. 7 is a section on the section line 7—7 of Fig. 4.

Fig. 8 is a fragmentary view showing a modified form of the invention shown in Fig. 4.

Fig. 9 is a horizontal section on the line 9—9 55 of Fig. 8.

Referring first to Figs. 1 to 3 of the drawings, it will be observed that a suitable base, a portion of which is shown at 1 and which is provided with an opening at 2 for the reception of 60 a discharge chute 3, supports a pair of laterally spaced upstanding frame members 4, each of which has at one end thereof a platform portion 5 for the support of pillow blocks 6, in which a transverse drive shaft 7 is mounted. The drive 65 shaft has a crank 8 thereon and is driven by a suitable driving pulley 9, which also performs the functions of a flywheel. A further flywheel 10 may be provided if desirable or necessary. Upon a higher portion of each of the side members 4 there is provided a mounting for a bearing 12. The bearings 12 support a transverse pivot shaft 13, upon which there is supported, in bearings 14, an oscillating chamber member 15, while between the bearings 14 for the chamber member 15 there is provided the pivotal

mounting or bearing at 16 for a depending, herein relatively heavy, size-reducing element 18. The casing member 15 has outstanding lugs 19 carrying a wrist pin 20 connected by a connecting rod 21 to the crank pin 8 of the drive shaft 7. 5 The chamber might oscillate upon a stationary shaft 13, or may be fixed to the shaft 13 and oscillate with the latter. The chamber member 15 is provided with an upstanding supply chute 23, into which there may be deposited material to be crushed, by any suitable means. At the opposite sides of the bearing 16 for the size-reducing (herein crusher) element 18, spaces are provided whose widths determine the maximum size of the material which may secure access to the 10 crusher element. The chamber-providing size-reducing element is provided with appropriate discharge means in the bottom thereof, as exemplified by the discharge slot 25.

The mode of operation of the device so far described will be readily apparent, as it will be appreciated that upon drive of the crankshaft 7 through any suitable belt means 26 and the driving pulley 9, the crank pin 8 will cause the connecting rod 21, through the wrist pin 20, to oscillate the chamber 15 at a rapid rate. So long as no material is fed into the hopper 23, the only motion, with appropriately arranged bearings, which would be imparted to the member 18 would be that due to the variations in air pressure at the opposite sides thereof, occasioned by the rapid oscillation of the chamber member 15. This will be insufficient to set the member 18 into motion of an amplitude to cause striking thereof by the chamber member 15, and accordingly, when no material is entering the chamber, there will be no impact between the relatively movable cooperative crushing elements. When, however, material begins to enter and to pass down at the opposite sides of the member 18, this material will set in motion the freely swingable member 18 and a cycle of operation somewhat as follows will take place during each complete oscillation of the casing member 15. As the casing swings in one direction, the material between the walls of the chamber therein and the member 18 will cause the latter to attain to the same angular velocity as the casing. The casing will, however, slow down during the motion of its crank in the second or in the fourth quadrant, 30 and then reverse its direction, while the freely pivoted member 18 will continue in its original direction of movement. There will accordingly occur an impact of one side of the casing and one side of the freely swingable member 18 upon 35 the opposite sides of a mass of material, with fracture thereof, and this will be followed by a reversal of motion of the freely pivoted member and the subsequent striking, on material at the opposite side of this member, of blows by the 40 opposite face of the freely pivoted member and the opposite end of the chamber member. It will be evident that a very efficient and powerful breaking action will be obtained; that mill breakage due to shocks or to the sticking of material which has to be crushed in order for the parts to move, is wholly avoided. It will be evident, moreover, that the material will be discharged very effectually by centrifugal force, and that the material, due to the point of feed 45 and the presence of the pivoted mounting for the freely swingable member, will be distributed most advantageously at opposite sides of the last mentioned member.

In the species of the invention shown in Fig.

4, it will be observed that a very similar apparatus has been provided except that in this case the member 18 is replaced by a member 28 which is pivoted upon a transversely extending bearing 5 providing member 29, which is supported by the casing member 30. This casing member is provided with a narrower throat 31 in order to control at that point the size of the material which may secure entrance to it after supply to a 10 hopper 32. In this form of construction it will be noted that due to the fact that as the chamber-providing casing 30 is oscillated the bearing member 29 will alternately assume positions at opposite sides of a position directly below the 15 pivot axis 33 upon which the chamber-providing casing oscillates, feed to the opposite sides of the freely swingable member 28 will be greatly facilitated. The mode of operation described in connection with the first species will have a 20 counterpart in the apparatus of Figs. 4 to 7, but it will be noted that in this form of the invention the member 28 has to its upper end motion imparted in a positive manner through the pivotal connection at 29, while its lower end derives 25 a motion through the material to be crushed. There is thus a limited freedom of motion, with a possibly more powerful blow to the material struck.

In the modified form of the apparatus shown 30 in Figs. 8 and 9, the difference from the construction shown in Fig. 4 resides primarily in the presence of a plurality of pivotally supported internal striking elements 28' and the increase in the size of the throat 31' and the provision of 35 transverse distributing members 35 below the point of pivoting of the chamber-providing member 30' so as to provide three passes A, B and C for the material to be processed and to effect delivery of this material at the opposite sides 40 of each of the internal pivotally supporting striking elements 28'. With this form of the invention there will be four crushing actions per cycle of movement of the chamber-providing member 30', and by this multiplication of the freely 45 swingable internal members there will be an increased capacity for material crushing.

In both the last forms the chamber-providing casing 30' will be sure to be pivoted on stub shafts 36.

50 It will be evident with respect to each of the forms of the invention described, that a very effective size-reducing or crushing operation will be accomplished, that the objects set forth above are effectually attained, that a very rugged apparatus is provided, practically proof against derangement, and that while a most powerful size-reducing or crushing action can be obtained from this device when normally used, power consumption will be almost in direct proportion to the 55 amount of work done, with a minimum of power consumption when the feed is interrupted.

While I have in this application specifically described two forms and a modification which my invention may assume in practice, it will be 60 understood that these forms and modification of the same are shown for purposes of illustration, and that the invention may be further modified and embodied in various other forms without departing from its spirit or the scope of the 65 appended claims.

What I claim as new and desire to secure by Letters Patent is:

1. In a size-reducing mill, a positively power- 70 oscillated size-reducing member providing a size- 75 reducing chamber having radial wall normal to

the planes of oscillation of said member, and a relatively movable size-reducing member within said chamber supported for free pivotal movement about an axis above its center of gravity and engageable at its lower end with said wall 5

2. In a size-reducing mill, a positively power-oscillated size-reducing member providing a size-reducing chamber having opposite end walls formed to act as hammers, and a relatively movable size-reducing member within said chamber providing oppositely facing hammer surfaces and supported for free pivotal movement about an axis above its center of gravity, so arranged with respect to said members that movement of said 10 second mentioned member upon said axis relative to said first mentioned member alters the conformation of the space within said chamber. 15

3. In a crushing mill, a positively power-oscillated crushing member providing a crushing 20 chamber, and a relatively movable depending crushing member within said chamber supported for free pivotal movement about an axis offset above its center of gravity, said members arranged for engagement with a hammering action 25 thereof.

4. In a crushing mill, a pivotally-mounted positively swingably power-oscillated crushing member providing a crushing chamber, and a freely- 30 swingable relatively movable crushing member within said chamber in spaced relation to the walls of the latter and partially dividing the interior thereof and supported for pivotal movement altering the chamber division about an 35 axis coincident with the axis of oscillatory movement of said first mentioned member and nearer one of its own ends than the other.

5. In a size-reducing mill, a positively power-oscillated size-reducing member having walls, including end and bottom walls, providing a size-reducing chamber, and a relatively movable size-reducing member extending within said chamber spaced from the bottom wall of said chamber in all positions of the latter and, when said chamber 45 is stationary in its mid position, spaced also from the end walls thereof and supported for free oscillatory movement towards and from the end walls of said chamber upon an axis offset both from the center of gravity of the portion thereof actually within said chamber and from the axis of oscillatory movement of said first mentioned member and engageable with said end walls. 50

6. In a crushing mill, a positively power-oscillated crushing member providing a crushing 55 chamber having generally radially-extending surfaces providing anvils, and a relatively movable depending crushing member within said chamber supported for free oscillatory movement upon an axis offset both above its own center of 60 gravity and from the axis of oscillatory movement of the first mentioned member and engageable with said anvil surfaces.

7. In a crushing mill, a pivotally-supported, positively-power-oscillated crushing member 65 providing a crushing chamber, and a relatively movable freely-suspended crushing member within said chamber supported for free oscillatory movement upon an axis disposed in a common plane with and offset from the axis of oscillatory movement of the first mentioned member but carried by said first mentioned member. 70

8. In a crushing mill, a pivotally-supported, positively power-oscillated crushing member providing a crushing chamber of maximum length 75

- at its bottom and having ends, and a relatively movable depending crushing member within said chamber supported for free oscillatory movement upon an axis offset from the axis of oscillatory movement of the first mentioned member but carried by said first mentioned member and having its lower end swingable through an arc to effect engagement with the chamber ends.
9. In a mill, a chamber member, a hammer member within said chamber member, said members pivoted on axes in the same straight line and each having blow-striking surfaces extending generally radially with respect to its pivot axis, and means for positively moving one of the same rapidly alternately in opposite directions to vary the space relations between said members and cause them to coact and engage with a hammering action.
10. In a mill, pivoted chamber and hammer members, each supported in depending relation to its pivot and with said hammer member having at least its blow-striking end within said chamber member, said members providing mutually engageable blow-striking surfaces and one pivotally supporting the other, and means for positively moving that member which pivotally supports the other member rapidly alternately in opposite directions to cause engagement of said blow-striking surfaces.
11. In a mill, a pivotally-supported, positively-power-oscillated crushing member having walls forming a crushing chamber and having means for conducting material into said chamber adjacent the axis of oscillation of said member, and a relatively movable crushing member within and spaced from the walls of said chamber and supported for free pivotal movement about an axis coincident with the axis of oscillatory movement of the first mentioned member and offset from its own center of gravity, said members providing surfaces retreating from and approaching each other and between which on their relative motion a crushing action is effected.
12. In a mill, a pivotally-supported, positively-power-oscillated crushing member providing a crushing chamber and having means for conducting material into said chamber adjacent the axis of oscillation of said member, and a relatively movable crushing member within said chamber supported for free oscillatory movement upon an axis parallel to and offset from the axis of oscillatory movement of the first mentioned member but carried by said first mentioned member.
13. In a mill, a pivotally-supported, positively-power-oscillated crushing member providing a crushing chamber and having means for conducting material into said chamber adjacent the axis of oscillation of said member, and a relatively movable crushing pendulum member within said chamber supported for free oscillatory movement upon an axis offset from the axis of oscillatory movement of the first mentioned member but carried by said first mentioned member, said pendulum member of a length and so pivoted that the same is engageable in widely swung positions thereof with a wall of said chamber.
14. In a crushing mill, a positively power-oscillated crushing member providing a crushing chamber, and a plurality of freely relatively movable crushing members within said chamber supported for pivotal movement and swingable relative to said chamber to alter the shape of the free space therein, the length of said mem-
- bers and their relative disposition providing for mutual engagement between them.
15. In a crushing mill, a positively power-oscillated crushing member providing walls bounding a crushing chamber, and a plurality of freely relatively movable crushing members within said chamber partially subdividing the interior thereof and supported for pivotal movement altering the subdivision and swingable into contact with each other and with certain of said chamber walls.
16. In a crushing mill, a positively power-oscillated crushing member providing a crushing chamber, and a plurality of relatively movable crushing members within said chamber supported for free oscillatory movement upon parallel axes carried by and moving with said first mentioned member upon oscillation of the latter.
17. In a mill, a positively power-oscillated crushing member providing walls bounding a crushing chamber, and a plurality of elongated freely relatively movable pivoted crushing members within said chamber with their elongation subdividing the chamber normally to its path of power oscillation and swingable into contact with each other and with certain of said chamber walls.
18. In a size-reducing mill, a positively pivotally power oscillated size-reducing member providing a size-reducing chamber and having radially-extending, blow-striking walls, and a relatively movable size-reducing hammer member extending within said chamber supported for pivotal movement upon an axis coincident with the axis of oscillatory movement of said first mentioned member and offset from the center of the portion of said second mentioned member actually within said chamber.
19. In a mill, relatively swingable chamber and hammer members coaxially pivoted and cooperating in forming a generally sector-shaped size-reducing space whose included angle alters with pivotal movement of either of said members relative to the other upon its respective pivot, said members having a limited free relative angular movement without contact with each other and each having hammering surfaces thereon, and means for positively moving one of said members rapidly alternately in opposite directions about its pivot to transmit motion to the other through material to be reduced to effect reduction of the latter between said hammering surfaces.
20. In a size-reducing mill, a positively swingably-power-oscillated size-reducing member providing a size-reducing chamber providing downwardly diverging opposite end faces, and a depending relatively movable size-reducing member within said chamber supported for pivotal movement about an axis coincident with the axis of oscillatory movement of said first mentioned member and having opposite end faces adapted to cooperate alternately with the diverging end faces of said chamber.
21. In a size-reducing mill, a positively swingably-power-oscillated size-reducing member providing a size-reducing chamber, and a relatively movable depending size-reducing member within said chamber supported for free oscillatory movement upon an axis above its center of gravity, the axes of said members disposed in a common plane, said chamber having a bottom conforming generally to the path of swing of the bottom of said relatively movable size-reducing member and out of contact with the latter, and said chamber also having ends between which

- and the opposite faces of the lower end of said relatively movable size-reducing member a hammering action may be alternately effected.
22. In a size-reducing member, a positively pivoted power-oscillated size-reducing member providing a size-reducing chamber having an arcuate bottom and opposite ends extending generally radially of said arcuate bottom, and a plurality of freely relatively swingable depending size-reducing members within said chamber supported for free pivotal movements on parallel axes between positions in which they are concurrently substantially parallel to said opposite ends.
23. In a size-reducing mill, a positively swingably-power-oscillated size-reducing member providing a size-reducing chamber having downwardly-diverging opposite end faces, and depending relatively movable size-reducing means with in said chamber supported for pivotal movement in the same planes with said chamber-providing member and providing mutually opposite sur-
- faces adapted to cooperate alternately with the diverging end faces of said chamber.
24. In a mill, a pivoted, positively-power-oscillated crushing member providing a crushing chamber having a plurality of radially extending walls, and a plurality of elongated movable crushing members within said chamber, said last mentioned crushing members disposed with their elongation extending parallel to a line normal to the path of oscillation of said first mentioned member at substantially the median point thereof when said first mentioned member is stationary and said chamber empty of material, and said last mentioned crushing members so mounted for free pivotal movement and so spaced relative to each other and to said radially extending chamber walls that they are movable, by forces transmitted to them through chamber-contained material to be crushed, into material-crushing proximity to each other and to said radially extending chamber walls.

ROBERT S. BUTLER.
